[57] ABSTRACT

This invention provides a strand chopping apparatus by means of which glass and other strands can be chopped into predetermined lengths without danger to the hands of an operator. The apparatus includes a backing roll and a cutter roll with blades projecting outwards so as to practically touch the backing roll so that strands introduced between the rolls are chopped into the required lengths. The backing roll has a frusto-conical end portion positioned to project through an aperture in a circular guard plate forming part of a guard assembly which also includes a guard box, a slot being provided between the guard plate and the guard box through which strands may be fed sideways into contact with the frusto-conical portion of the backing roll.

TREATMENT OF GLASS FIBRES

This invention is concerned with the provision of a safety device for use in connection with chopping apparatus for cutting continuous glass or other strands into lengths.

In conventional chopping apparatus a glass strand is fed in between a cutter roll and a backing roll so that the strand is cut into short lengths. Usually the cutter roll has radially extending blades which project into shallow slots in the backing roll as the two rolls rotate. This kind of chopping apparatus is very effective in operation but there is a safety problem in that each strand has to be fed manually into position between the rolls. This leads to the possibility of an accident when the strands are being fed to the high speed chopper which is normally arranged in line with a bushing from which filaments are drawn and combined into strands.

One object of the present invention is therefore to provide means to avoid any possible danger to an operator who initially feeds a strand into a chopping apparatus.

In accordance with the present invention we provide strand chopping apparatus comprising a backing roll and cutting means associated with the backing roll so that a strand introduced between the backing roll and the cutting means is cut into predetermined lengths characterised by the provision of a frusto-conical portion on the backing roll and a slotted guard device shaped to prevent the hand of an operator being caught between the roll and the cutting means and to guide a strand through the slot to contact the conical part of the backing roll.

The guard device preferably includes a box like guard provided with an opening through which the frusto-conical portion of the backing roll projects. The guard device also preferably includes a substantially circular guard plate arranged around the frusto-conical portion of the backing roll and provided with an in-turned lip. The cutting means is preferably in the form of a cutter roll with projecting blades.

In operation when cutting strands formed by extrusion from a bushing the axes of the cutter roll and the backing roll are preferably in substantially the same vertical plane, but when cutting strands from rovings or cake creels the axes of the cutter roll and the backing roll may be in substantially the same horizontal plane.

In order that the invention may be more clearly understood and readily carried into effect reference is now directed to the accompanying drawings given by way of example in which:

FIG. 1 is a diagrammatic side elevation of apparatus embodying the invention.

FIG. 2 is a section on A—A of FIG. 1 and

FIG. 3 is a partial view showing how a cutter roll, usually called the chopper body, co-operates with a backing roll.

In FIG. 1 a strand 1 is seen descending from a bushing indicated generally at 10, a backing roll is shown at 2 and a cutter roll at 3 with blades 9, a circular or similar guard plate 4 being provided around the end of the backing roll which projects through an opening in the wall of a second or box-like guard 8. Referring to FIG. 2 it will be noted that the backing roll 2 has a frusto-conical portion 5 at the projecting end and that the guards 4 and 8 are shaped to provide an aperture or slot

6 through which the strand 1 can be introduced into the apparatus.

In operation the rolls 2, 3, are set to run at say 200 to 300 feet per minute and the strand 1 is hand-pulled vertically downwards in the direction of the arrow A in FIG. 1 so that it extends behind a part of an inturned lip 7 on the guard 4 see FIG. 2. The strand end below the guard 4 is then moved smoothly to the right in FIG. 1 in the direction of the arrow B and at the same time the drawing motion is continued. In this movement the strand 1 is brought from the position C in FIG. 2 through the aperture 6 to the position D. As soon as the strand 1 makes contact with the frusto-conical end 5 of the backing roll 2 the strand begins to travel up the conical surface and becomes nipped between a blade on the cutter roll 3 and the backing roll 2. As soon as this occurs the speed of the rolls 2 and 3 is increased to the required running speed, at which the apparatus is self-clearing, and the lengths chopped on starting up are thrown clear. Further than that the rapid rotation of the rolls 2, 3, is sufficient to ensure that the strand 1 continues to be drawn downward so that successive lengths of strand are chopped as the machine continues to operate.

It will be noted that the guard 4 is completely circular and the mounting means (not shown) is preferably positioned at the top right hand quarter where it does not interfere with the strand or strands. The guard 8 is essentially a box with a hole cut in it to allow the end core of the roll 2 to project and also providing a slot or aperture 6 so positioned that a running strand can enter the nip laterally and the slot is extended horizontally to allow the strand to be pulled into the nip. It will be understood that any reasonable number of strands can be cut simultaneously, the strands either being fed in together as one strand and subsequently separated or being fed in strand by strand one after another when the machine is running so that the strands distribute themselves along the rolls 2 and 3.

Although in the above description we have referred to a guard 4 and a second guard 8 the guards may be regarded as forming a single guard assembly to offer a safeguard to an operator and with a slot or aperture to allow the strands to pass into the apparatus.

Whilst the previous description relates particularly to use of the invention for cutting strands which have been obtained by vertical drawing from a bushing, the present invention is also of use for cutting strands from rovings or cake creels. For these latter purposes it is normal to supply roving in a horizontal direction to a cutting apparatus which chops the roving and subsequently delivers the chopped strands in a downward and substantially vertical path. In this respect the present invention would be operably arranged with the axes of the cutter roll 3 and backing roll 2 parallel and in a common horizontal plane. Effectively this amounts to rotation of FIG. 1 of the accompanying drawings through 90°. However, though this arrangement is to be preferred, the cutter and backing rolls may be orientated in any manner suitable for carrying out chopping.

Although starting speeds of 200 – 300 feet/minute are mentioned in the general description of the cutter and its operation, greater starting speeds, say up to 700 feet/minute, may be used if the material being chopped will withstand such starting speeds.

I claim:

1. A strand chopping apparatus comprising a backing roll and a cutter roll with projecting blades associated with the backing roll so that strands introduced between the backing roll and the cutter roll are into predetermined lengths characterized in this, that the backing roll is provided with a frusto-conical end portion positioned to project through an aperture in a guard box forming part of a guard assembly which also includes a substantially circular guard plate, a slot being provided between the guard plate and the guard box through which in operation strands are moved sideways into contact with the frusto-conical end portion of the backing roll which guides the strands into a position in

which they are nipped between a cutting blade and the backing roll and are chopped into predetermined lengths.

5 2. An apparatus according to claim 1 characterised in that the axes of the cutter roll and the backing roll are in substantially the same vertical plane.

10 3. An apparatus according to claim 1 characterised in that the axes of the cutter roll and the backing roll are in substantially the same horizontal plane.

15 4. The apparatus of claim 1 in which the guard plate is provided with an inturned lip.
